ENGINE STARTER

Application filed October 24, 1929. Serial No. 402,236.

This invention relates to engine starters and more particularly to the inertia type of starter in which the starter pinion is mounted on a screw shaft so that it will be moved by the rotation of the shaft longitudinally thereof into mesh with an engine gear and will then be rotated with the shaft to drive the gear and our object is to provide a device of this character which will readily mesh with the engine gear.

We attain our object by providing the screw shaft with two starter pinions arranged on opposite sides of the engine gear. The teeth of the pinions are so arranged that the teeth of one pinion are out of alinement with the teeth of the other pinion when the pinions arrive at their positions for meshing with the gear. The chances of one of the pinions moving axially directly into mesh with the gear are thus increased and should both pinions collide with the gear the rotary movement necessary to mesh one of them therewith would be not more than half that required in the case of a single pinion.

The constructions are hereinafter more fully described and are illustrated in the accompanying drawings in which—

Fig. 1 is a side elevation of our improved starter showing the pinions in their normal 30 inoperative positions;

Fig. 2 a view similar to Fig. 1 showing the pinions after they have been moved axially towards the gear;

Fig. 3 a cross section on the line 3—3 in Fig. 2 showing the teeth of one of the pinions in contact with the teeth of the gear, the teeth of the other pinion being in alinement with the spaces between the gear teeth;

Fig. 4 a view similar to Figs. 1 and 2 showing the starter positioned for driving the engine gear, one pinion being meshed with the gear as shown in full lines, and both pinions partly in mesh in dotted lines; and

Fig. 5 a detail showing the starter positioned for driving the gear with one pinion in mesh therewith.

In the drawings like numerals of reference indicate corresponding parts in the different figures.

1 is the armature shaft of a starter motor

(not shown) and on the shaft is threaded two starter pinions 2 and 3 either one of which is adapted to mesh with a gear 4 of the engine to be started. The threads 2^a and 3^a, for the pinions 2 and 3, are directed oppositely to one another so that both pinions, due to their inertia, are moved towards the gear when the shaft 1 is rotated by the starter motor. The teeth of the pinions are so arranged that the teeth of one pinion are substantially half a tooth ahead of the teeth of the other pinion when the pinions arrive at their positions for meshing with the gear as shown in Figs. 2 and 3. In these views the teeth of the pinion 2 are in register with the spaces between the teeth of the gear 4 so that the said pinion will be moved into mesh therewith. As soon as the pinion teeth enter between the gear teeth the latter prevent rotation of the pinion 2 which is then fed by the thread 2^a until it meets the pinion 3, the threads 2^a and 3^a being crossed to permit either pinion being meshed with the gear.

When the axial movement of the pinion 2 is stopped, upon meeting the pinion 3, the pinions will rotate with the shaft whereby one or both pinions will drive the gear and will be de-meshed in the usual manner when the engine is started. Abutments 5 and 5^a carried by the shaft limits the de-meshing movement of the pinions 2 and 3 respectively.

Should the teeth of the pinion 3 register with the spaces between the teeth of the engine gear 4 when the pinions arrive at their positions for meshing with the gear, the pinion 3 will mesh with the gear and be fed, by the thread 3^a, until it meets the pinion 2.

In case the teeth of both pinions collide with the teeth of the gear, the axial movement of both pinions will be temporarily stopped and the gear will be frictionally gripped between them. The starter will now operate as a frictional grip drive turning the gear and rolling thereon until such time as the teeth of one of the pinions mesh with the teeth of the gear. As the pressure of the pinions on opposite sides of the gear is equal there is no tendency to move the shaft axially and thus jam it against its bearings. On account of the hereinbefore mentioned

arrangement of the teeth of one pinion relative to the teeth of the other pinion, the relative rotary movement of the pinions and gear necessary to permit clearance for the 5 teeth of one of the pinions will be not more than half the circular pitch of the gear.

When the thread is of usual pitch for this type of starter, it is obvious that the pinions will meet in various positions depending on 10 the rotary movement necessary to mesh the first pinion. In Fig. 4 we have shown in full lines the pinion 2 only in mesh with the gear 4 in which case this pinion has required very little or no rotary movement to mesh it with 15 the gear and has been fed by the thread 2^a into contact with the pinion 3 before the latter has been meshed with the gear 4. In the dotted lines in Fig. 4 the meshing of the pinion 2 has been delayed, thus both pinions have been rotated simultaneously and, while 20 the pinion 2 has been meshed first, the rotation of the shaft 1 to feed the pinion 2 along the shaft has resulted in the meshing of the other pinion 3 with the gear 4. Both pinions 25 are thus meshed with the gear. In either of the above-mentioned cases the pinions when they meet will be restrained from further axial movement by the equal pressure of one against the other whereby the 30 gear will be driven. It is obvious that if the threads 2^a, 3^a be of very long pitch, the pinion first meshed with the gear will force the other pinion axially until it engages its abutment 5 or 5^a which limits the axial movement 35 of the pinion in mesh with the gear to cause the last-mentioned pinion to be rotated with the shaft to drive the gear, see Fig. 5.

What we claim is:

1. In an engine starter drive the combination of a rotatable shaft; two starter pinions mounted thereon for rotary movement therewith and for longitudinal movement thereof to mesh with a gear of an engine to be started, and means for moving the pinions towards the gear, the pinions being disposed on opposite sides of the gear and having their teeth arranged so that the teeth of one pinion are out of alignment with the teeth of the other pinion when the pinions arrive at 45 their positions for meshing with the gear.

2. In an engine starter drive the combination with a gear of an engine to be started, of a rotatable shaft; two starter pinions mounted thereon for rotary movement therewith and for longitudinal movement towards one another and the gear; and means for causing such longitudinal movement of the starter pinions by the rotation of the shaft, the pinions having their teeth arranged so that 55 the teeth of one pinion are out of alignment with the teeth of the other pinion when the pinions arrive at their positions for meshing with the gear.

3. In an engine starter drive the combination with a gear of an engine to be started,

of a rotatable shaft having right and left hand threads, two starter pinions threaded on the said threads for longitudinal movement towards one another and the gear by the rotation of the shaft.

70

4. In an engine starter drive the combination with a gear of an engine to be started, of a rotatable shaft having right and left hand threads, two starter pinions threaded on the said threads for longitudinal movement towards one another and the gear by the rotation of the shaft, the said threads being crossed to permit either pinion to fully mesh with the gear.

75

Signed at Toronto, Canada, this 19th day 80 of October, 1929.
